LUIS MARTINEZ-SILVA, OF BOGOTA, COLOMBIA.

AUTOMATIC MECHANISM FOR FIREARMS.

1,233,096.

Specification of Letters Patent. Patented July 10, 1917.

Application filed May 5, 1914. Serial No. 836,406.

To all whom it may concern:

Be it known that I, LUIS MARTINEZ-SILVA, barrister, a citizen of the Republic of Colombia, and residing at Rue 14, No. 18, Bogota, Republic of Colombia, have invented 5 certain new and useful Improvements in Automatic Mechanisms for Firearms, of which the following is a specification.

The object of the invention is an automatic mechanism for automatic fire arms of 10 the kind in which one portion of the gases produced by the burning of the charge in the cartridge is introduced into the mechanism for the purpose of acting on the different members of same.

15 The mechanism about to be described is characterized essentially:

By the fact that it comprises two springs (one for opening the breech and the other 20 for closing same) which are compressed simultaneously by a single member acted upon by a piston which is operated by the gases.

By the fact that the opening spring cannot 25 expand, for the purpose of opening the breech, until the ball has issued from the barrel;

By the fact that the gases which operate 30 the mechanism are drawn off, from the barrel, at a comparatively long distance from the breech;

By the fact that all parts of the mechanism which are liable to foul can be cleaned 35 by drawing out a single member, and without having to remove the stock.

By the fact that the principal mechanism is inclosed in two tubes screwed one within 40 the other and each forming an extension of the other, so that the two form a whole.

By the fact that, by virtue of its relation 45 with the breech members, this automatic mechanism has no effect at all on the operation of the weapon when the latter is fired, non-automatically, by hand, provided the gas intake be closed.

Finally, by the fact that the automatic mechanism is maintained in the position corresponding to opening the breech, as soon 50 as the shell of the last cartridge contained in the magazine has been ejected. This result is obtained by means of members which, in contradistinction to those existing in other systems, are strongly made.

The simultaneous compression of the two 55 springs presents two chief advantages: in

the first place it opposes to the high power of the gases, all the resistances of the mechanism at once, so that the gases encounter the maximum resistance which the mechanism is capable of offering, the result being 60 to reduce the violence with which the members are displaced to a minimum. The other advantage consists in the fact that the opening spring may be relatively weak, and therefore comparatively light, since its chief 65 work, at the commencement of its expansion, consists solely in unlocking the breech bolt and cocking the weapon.

The fact that the opening spring cannot 70 expand until the ball has issued from the barrel, prevents the breech from being opened prematurely—an accident which might have serious consequences.

The location of the gas intake at a distance enables the gases to enter the automatic mechanism with a minimum of residue, heat and force.

The simplicity of the operation necessary for cleaning all the parts of the mechanism which are liable to foul as the result of contact with the gases, enables the cleaning to 80 be performed quickly and without risk of losing any of the pieces.

The aggregate formed by the two tubes containing the chief members of the mechanism should not be taken apart to fit it on the weapon, being capable of being withdrawn and replaced as a whole and with great facility. Moreover, since the parts contained in the tubes are not exposed to 90 contact with either the gases or rain, it is not necessary for them to be taken apart, though this operation can be performed by simply unscrewing the tubes, which, on coming apart, reveal all the internal members. 95

By means of an automatic device which, on the one hand, reliably insures combination between the automatic mechanism and the breech mechanism in opening and closing the breech, and on the other makes these 100 two independent of each other when the breech is closed, the marksman can, at will, open and close the breech by hand, without affecting the movable members of the automatic mechanism. To change from automatic to non-automatic firing (consecutive or single shots) all that is necessary is for the marksman to close the gas intake, leading to the automatic mechanism, by acting 105 on a single member.

Finally, in consequence of the breech being maintained in the open position when the last cartridge in the magazine has been ejected, the marksman, being thus warned 5 that the ammunition of the firearm is exhausted, can easily recharge the magazine; and in order to close the breech, all that he has to do is simply to pull the breech bolt lever, which is then automatically brought 10 into the closing position. The various members composing this device cannot be touched by the marksman, and therefore the breech cannot be closed by accident.

The invention is illustrated, by way of 15 example, in the accompanying drawings, in which:

Figure 1 represents, in elevation, a longitudinal section of the automatic mechanism;

Fig. 2 a detail of the mechanism, in plan 20 and on a larger scale;

Figs. 3 and 4 are diagrammatic views enabling the working of the mechanism to be understood;

Figs. 5, 6, 7 and 8 are cross sections, 25 along the lines *a—a*, *b—b*, *c—c* and *d—d* respectively of Fig. 1, and viewed from the front;

Fig. 9 is a perspective view of the device controlling the gas cock;

Fig. 10 is a view, on a larger scale, of the safety device which prevents the breech from being opened before the ball has left the weapon:

Figs. 11 and 12 show two constructional 35 modifications of one of the members of this device;

Fig. 12' shows another constructional modification of this device;

Figs. 13, 14, 15 and 16, 17 and 18 are 40 diagrammatic views showing three constructional modifications of the gas piston, in elevation and cross section respectively;

Fig. 19 is a view of the breech block, the right hand portion of which is supposed to 45 have been removed, thus enabling the internal members to be seen, these being shown in the open position;

Fig. 20 is a similar view, the members being in the closed position;

Fig. 21 is a constructional modification 50 of the automatic assembling device;

Fig. 22 represents a cross section along the line A—B of Fig. 20;

Fig. 23 is a view of the breech, the right 55 hand portion being supposed to have been removed, in order to show the operating rod;

Fig. 24 is a view, in vertical section, of the lower front part of the breech block, on a larger scale;

Fig. 25 shows a cross section along the 60 line C—D of Fig. 24; and

Fig. 26 is a horizontal section along the line E—F of Fig. 24.

The automatic mechanism consists of a 65 cylinder 1, into which the gases coming from

the barrel are conveyed through a passage 2. The cylinder may be cast in one piece with the barrel, or may be fitted thereto and finished in any suitable way. A cock 3, 70 screwed into the front end of the cylinder 1, enables the gas passage to be opened or closed, with which object the cock is formed in such a way as to exhibit, on the end which penetrates into the cylinder, a notch 4, which allows the gases to pass through when the 75 cock is in the position indicated in Fig. 1. On the other hand, when the cock 3 is turned half way around by means of the handle 5, as shown in Figs. 5 and 9, the notch 4 takes up a diametrically opposite position, which 80 corresponds to the gas passage being closed. A fork 6, the stem of which engages in the body of the cylinder 1, and the branches of which form springs, keeps the cock 3 fixed in one or other of these two positions. A 85 piston 7, formed of a solid rod, is housed in the cylinder 1.

Behind the cylinder 1 are two cylindrical tubes 8 and 9, screwed one into the other and in the same straight line. These tubes contain a rod 10, the thickened front end 11 of which serves as an abutment for the opening spring 12, the second abutment of which is formed by a block 13 surrounding the rod 10, the rear end of which rod is provided with a thread on to which a second block 14 is screwed, being maintained in position by a locking nut if required. Finally, the closing spring 15 is housed between the block 14 and a plug 16 screwed 100 into the rear end of the tube 9. This plug 16 is secured by means of a screw 17, which also serves to keep in place a member 18 mounted on the left hand side of the tube 9, with which it engages, in the first place, by means of a dovetail. This member takes the form and plays the part of a hook, the body of which is formed of a flexible blade.

Above the point at which the block 13 is situated when the mechanism is at rest, is 110 located another passage 19, which enables a small portion of the gases to enter a chamber 20 provided with a piston 21 which carries a tooth 22 engaging in a perforation provided in the bottom of a socket 23 which is screwed into a thickened part of the barrel. The tube 9 is cut away below the tooth 22, so as to enable said tooth to drop into a notch 24 provided in the upper part of the block 13.

Lugs 13^a, 13^b and 14^a, 14^b, are secured to, or cast in one piece with, the blocks 13 and 14, respectively and protrude from the tube 9 through longitudinal openings 9^a and 9^b respectively provided in the sides of said 125 tube.

A rod 25, coming, on the right hand, from the breech block 29, and serving to transmit the movements of the automatic mechanism to the breech members, bears against the 130

tube 9, a portion of which is shaped away for that purpose. At the upper side the rod 25 is held by projections 26, made in one piece with the tube 9 and serving at the 5 same time to hold the tube in position with relation to the barrel. In cross section the rod 25 is U-shaped, the two limbs of the U being joined, at a suitable point, by a rib 25'. When this rod is placed in position 10 against the tube 9, the rib 25' engages between the lugs 13^a and 14^a of the blocks 13 and 14. Moreover, the rod 25 is held and guided by the stock 27, which is fitted, for this purpose, with a thin strip of steel 28. 15 The stock 27 is put in position by placing it against the under side of the mechanism, and is held there by means of a sling ring and band.

The automatic mechanism acts in three 20 stages, which succeed one another in the following manner:

Preparatory stage or setting the mechanism.—Fig. 1 shows the mechanism in the position of repose. When, after firing the shot, the ball has passed the gas intake passage 19 in the barrel, a small portion of the gases forces the piston 21 downward and keeps it in contact with the bottom of the socket 23. At the same time the tooth 22, 25 which is in one piece with the piston 21, is held in position in the notch 24 of the block 13, which is thus rendered immovable. When the ball has passed the main gas intake passage 2, a portion of the gases forces 30 the piston 7 backward. The piston 7 pushes the rod 10, and at the same time compresses the opening spring 12 against the block 13, which is fixed, and the closing spring 15 against the plug 16. During this movement 35 the lugs 14^a and 14^b of the block 14 slide in the longitudinal openings 9^a and 9^b; and at the same time the lug 14^a slides in the recess in the rod 25. Toward the end of its stroke 40 the lug 14^b raises the hook 18 which, in consequence of its flexibility, drops down in front of this lug as soon as the latter has passed the tooth of the hook, so that the block 14, and consequently the rod 10, cannot return in the forward direction under 45 the thrust of the two springs 12 and 15, which are therefore kept in the compressed condition. Fig. 3 shows the mechanism in this position.

It will be evident that if the ball remained 50 in the barrel, between the passage 2 and the muzzle, the gas pressure would be maintained, and therefore the block 13 would remain immovable.

Opening-the-breech stage (release of the opening spring 12).—As soon as the ball has issued from the barrel, the gases escape from this latter, the cylinder 1 and the chamber 20. Consequently, the tooth 22 is no longer held down in the notch 24, except 55 by its own weight and that of the piston 21.

Forced by the spring 12, which expands, the block 13 then raises the tooth, by reason of the inclined planes with which the tooth and the notch are provided, and pushes the rod 25 rearward by the aid of the lug 13^a, which bears against the rib 25'. This is the 70 opening-the-breech stage.

Fig. 4 shows the mechanism at the end of its opening stroke.

Closing-the-breech stage (expansion of the closing spring 15 and return of all the members to their initial position).—When the block 13 arrives at the end of its stroke, its lug 13^b raises the stop hook 18, which releases the lug 14^b and consequently the 75 block 14, which is then pushed forward by the closing spring 15. The lug 14^a pushes the rod 25 forward, by bearing against the rib 25' which came into contact with the lug 14^a at the end of the opening stroke. The 80 rod 25 in turn brings all the breech members into the closing position, the weapon being cocked. The latter is then ready for firing another cartridge, without the marksman having had to move the weapon from his 85 shoulder. When the closing stage is completed, the members of the automatic mechanism occupy the position shown in Fig. 1, that is to say are at rest. 90

In moving forward again the block 14 95 and the rod 10 have drawn with them the block 13 and spring 12. Owing to the slight tension still possessed by the spring 12, all these members remain in contact during this stage and form a rigid aggregate. At the 100 same time the piston 7 is pushed forward again.

The efficiency of the safety device, which prevents the breech from being opened so long as the ball has not issued from the 105 barrel, can easily be demonstrated in the following manner:

The tooth 22 is kept bearing in the notch 24 by a force which, for the sake of simplicity, may be assumed as equal to that which effects the simultaneous compression of the two springs 12 and 15. The spring 15, which is necessarily more powerful than the spring 12, absorbs about two-thirds of the force required for the simultaneous compression of the two springs, whence it follows, inversely, that the force of the opening spring 12 is less than one-third the force of the gases. Consequently, the tooth 22 is held by a force at least three times as great 110 as that which the spring 12 tends to exert when compressed; but, in addition, the spring 12 must, in order to open the breech, overcome the resistances presented by the unlocking of the tenons of the breech bolt. 115 These resistances are much greater during the course of the ball toward the muzzle of the barrel, owing to the pressure exerted by the gases on the head of the breech bolt. In 120 these conditions it will be evident that the 125 130

available force of the spring 12, diminished by these resistances, remains very small until the ball has issued from the barrel; and this force is opposed, through the agency 5 of the tooth 22, by the force of a portion of the gases, which force was sufficient to compress the two springs simultaneously.

Fig. 10 shows a tooth with a pointed tip like a center punch: in Fig. 11 the end of 10 the tooth is rounded: and finally in Fig. 12 the tooth is of square section, with wedge shaped tip. Other modifications of shape than those illustrated here as examples may 15 easily be imagined, the essential point being to get the end of the tooth 22 to engage with the block 13 and, by means of the inclined planes or rounded shape, to enable this tooth to be lifted vertically by the block, which moves in a direction at right angles 20 thereto.

The device shown in Fig. 12'—provided the head 21' of the piston comes flush with the interior of the barrel—presents the advantage of preventing any permanent deposit of residue. Hence, there is no need 25 for the device to be frequently cleaned.

In Fig. 1 the chief piston 7 is shown as though formed of a solid rod. Constructional modifications are illustrated in Figs. 30 13 to 18.

Figs. 13 and 14 show a piston the weight of which is reduced by the provision of longitudinal channels.

Figs. 15 and 16 represent a piston of a 35 shape which enables the gas, on arriving in front of the end of the piston, to enter, first of all, into chambers or open spaces situated above, below or even at the sides. The piston is then acted upon by the gases 40 continuing to arrive through the passage 2, and, in proportion as the piston recedes in the cylinder 1, a counter-pressure, due to the gases partially surrounding the piston, is set up in the cylinder, and the force of 45 impact of the gases against the piston is thus lessened. The piston might also be constructed in such a way as to leave only one chamber.

Figs. 17 and 18 show a piston, the front 50 portion of which is hollowed out for a certain distance, the rearward portion being solid. The object of this form is to insure a perfectly tight joint between the piston and the cylinder in which it travels, in 55 sequence of the radial thrust exerted by the gases against the inner periphery of the hollow. Moreover, since the pressure of the gases is chiefly directed against the base of the cavity of the piston, that is to say 60 about half way along the piston, the resistance of the latter is considerably increased.

In order to clean out the cylinder 1, all 65 that is needed is to unscrew the cock 3 completely, and then cause the piston 7 to drop

out by holding the weapon vertically, barrel downward.

To clean out the safety device (piston 21) it is sufficient—after having removed the stock, and the tubes 8 and 9 (together) 70—to unscrew the socket 23. The trunconical shape of the chamber 20 enables the piston 21 to expel any residues which may have been deposited on it, through the passage 19.

To remove the automatic mechanism as a whole, the weapon must be tilted slightly toward the left, after having removed the stock, the cock 3 and the piston 7, whereupon the tubes 8 and 9 drop out of their 80 own accord.

These tubes are held, at the rear end, by a nipple forming part of the plug 16 and at the front end by the piston 7, which projects slightly beyond the cylinder 1.

In Fig. 1 the handle of the bayonet carries a heel piece 30 which bears against the solid part connecting the barrel with the cylinder 1, so that the cock 3 can be operated even when the bayonet is fixed.

Connection between the automatic mechanism and the movable members of the breech block is established, through the operating rod 25, by means of the following device, shown on Figs. 19 to 22.

On the upper side and near its rear end, the operating rod 25 is provided with a lug 31, which bears against a projection 32 arranged on the lower edge of the sleeve 33. By the aid of a slanting groove 34 provided in the sleeve 33, and in which the tenon 35 of the breech bolt 36 engages, the longitudinal rectilinear movements of the sleeve 33 effect the opening and closing of the breech, in the known manner. A hook shaped member 37 is hinged at 38 on the end of the rod 25. When the members are in the position of repose, the hook 37 tends to drop, by its own weight and pivoting on the point 38, into a recess 39 provided in the horizontal part of the slide in which move the rod 25 and the lower portion of the sleeve 33, the rectilinear movement of which is insured by means of ribs 40 engaging in corresponding grooves in the 100 breech casing.

Near to the pivot 38 the hook 37 is provided with a claw 41 which, when the members are in the position of repose, abuts against a projection 42 in one piece with the wall of the breech casing, so that the hook 37 is forcibly held embedded in the recess 39.

Under these conditions the marksman can at all times open and close the breech by working the operating lever 43, without moving the hook 37 and rod 25, and therefore without having to overcome the resistance of the springs of the automatic mechanism.

5 The shocks transmitted to the weapon when the same is being operated by hand cannot in any case raise the hook 37, the claw 41 of which is held forcibly in contact with the projection 42.

When the weapon is set for automatic firing, the rod 25 moves backward, in the first place, pushing the sleeve 33 backward by means of the lug 31, and also, by means 10 of the pivot 38, moving backward the hook 37, the claw 41 of which detaches itself from the projection 42. At the beginning of this movement, the head of the hook 37 comes in contact with an inclined plane 44 which 15 compels the hook 37 to pivot and come in contact with the sleeve 33. When the members are in the position shown in Fig. 20, and the hook 37 is in contact with the horizontal portion of the slide, the engagement 20 of the hook 37 and the sleeve 33 is complete. The rod 25 continues its rearward course and then, under the influence of the automatic mechanism, returns in the forward direction to close the breech. It will 25 be easily understood that, in returning in the forward direction, the rod 25 draws with it the sleeve 33, by means of the assembling hook 37, the tooth 45 of which is in engagement with the projection 32. 30 Owing to the resistance set up by the locking of the tenons of the breech bolt toward the end of the return stroke of the rod 25, the hook 37 still remains engaged with the sleeve 33 by contact, although the weight 35 of the hook 37 tends to cause it to drop when it arrives over the recess 39. For this purpose the sleeve must commence to lock the breech bolt before the hook 37 is completely engaged above the recess 39. In 40 the last few millimeters of the return stroke, the claw 41 strikes against the projection 42, which compels the hook 37 to drop into the recess 39.

A constructional modification is shown in 45 Fig. 21. The assembling member or cam 46 is hinged toward the rear on the end of the rod 25, which is necessarily longer than in the previous example. As in the case of the hook 37, a claw 41 and a projection 42, 50 insure the lowering of the cam 46 into a recess 39, the inclined surface 44 of which compels the cam 46 to come into engagement with the projection 32 on the sleeve 33.

It will be understood that the dimensions 55 and proportions of the hook 37 or of the cam 46 may be varied according to the shape of the breech members.

The movable members of the breech and the automatic mechanism are automatically 60 fixed in the position corresponding to the opening of the breech, (as soon as the shell of the last cartridge contained in the magazine has been ejected), by means of the following device, which is shown in Figs. 65 23 to 26.

A pawl 48, held by a shaft 49, the base of which is threaded so as to screw into the breech casing, engages in a recess 47 provided in a forward extension of the breech casing 29, as shown in Fig. 24. An 70 arm 50, in one piece with the pawl 48, serves as abutment for a weak spring 51, the second abutment of which is formed by a screw 52, hollowed out to house same. This screw 52 also serves to retain a plate 75 53 dovetailed into a recess in the side of the breech casing and serving to close the mouth of the recess 47. An opening 54 places the recess 47 in communication with the slide in which moves the operating rod 80 25 of the automatic mechanism.

On the other hand, the cartridge carrier 56 is provided with a finger 55, which is hinged on the cartridge carrier and penetrates into a groove 57 arranged in the bottom of the front end of the magazine. The left wall (Fig. 25) of the groove 57 is in the extension of the corresponding side of the magazine, in order that the points of the balls shall not enter it. As can be seen 90 from Fig. 25, the pawl 48 is of such a shape as to present, in front of the upper part of the groove 57, a surface 58 sloping at an angle of about 45 degrees.

At a suitable point the two parallel edges 95 of the rod 25 are connected by a rib 59, which exhibits an inclined surface 60 and a sharp edge 61. The position of this rib is determined by the distance the rod 25 has to travel in order to open the breech, bearing in mind that this rib should come into position a little beyond the opening 54 when the breech is fully open.

The system operates in the following manner:

In proportion as the cartridge carrier ascends during the automatic firing of the cartridges contained in the magazine, the finger 55, being hinged, rises in the groove 57 and, when the last cartridge has been 110 inserted into the barrel, the cartridge carrier assumes the position shown partly by broken lines and partly by full lines, in Fig. 24. During the last stage of the ascent of the cartridge carrier, the finger 55 is in 115 contact with the inclined plane 58. Owing to the force of the springs lifting the cartridge carrier, the finger 55, in ascending, pushes the pawl 48 toward the right, by overpowering the force of the small opposing spring 51 which, up to now has kept the pawl in front of the groove 57. In pivoting about the point 49, the pawl 48 pushes its finger through the opening 54 into the groove 25' of the rod 25. When the last 120 cartridge has been fired, the automatic mechanism comes into action and forces the rod 25 to the rear to open the breech. Toward the end of this rearward stroke, the slope 60 on the rib 59 encounters and pushes 125 130

the tooth of the pawl 48 which, as soon as the edge 61 of the rib 59 has passed beyond it, is pushed back into the groove 25' by the constant effort of the lifting springs of 5 the cartridge carrier. Under these conditions, when the rod 25 moves forward again, the rib 59 meets the tooth of the pawl, which thus opposes the closing of the breech. The pawl and rod engage quietly, owing 10 to the fact that the rod is blocked as soon as it has passed the dead point. With regard to the resistance offered by the pawl, to hold the rod 25, in spite of the effort of the return spring of the automatic mechanism, the pawl 48 is provided at 62 with shoulders which produce this result by bearing against the corresponding parts of the breech block.

In order to effect the closing of the breech 20 when the magazine is full, the marksman has merely to pull the operating lever 43 of the sleeve 33 backward for a short distance, which sleeve moves the rod 25, and, as the cartridge carrier is down in the bottom 25 tom of the magazine, as soon as the rib 59 is detached from the pawl, this latter returns to its initial position under the thrust of the spring 51. The automatic mechanism is then able to draw forward the rod 30 25 and close the breech.

If the marksman has to close the breech, leaving the magazine empty, he must first place a cartridge in the magazine, then pull the operating lever to effect the automatic 35 closing of the breech and the insertion of the cartridge into the barrel. The sleeve 33 being detached automatically from the rod 25, in consequence of the automatic depression of the pawl 37, the marksman can then 40 open the breech by hand and take out the cartridge by withdrawing it from the extractor, after which he recloses the breech and uncocks the weapon as in an ordinary gun.

45 It may be mentioned that none of the members composing this system projects outside the breech casing, and that, consequently, the marksman cannot suddenly stop or close the breech accidentally by touching 50 the system inadvertently.

What I claim is:

1. In automatic small arms, in which the breech mechanism is actuated by the gases produced by the explosion of a cartridge, in which a part of the rod of the automatic mechanism engages with the front of the movable member of the breech when the latter is in closed position, and when being opened by said automatic mechanism, a pivoted member carried by said rod, a hook like projection on said member adapted to engage with the movable member of the breech mechanism on the opening of the breech and until it has been closed thereby, means on the breech casing for effecting the disengagement of the pivoted member from the breech member on the complete closing of same and a recess in the breech casing in which the pivoted member rests when in 70 inoperative position.

2. In automatic small arms, in which the breech mechanism is actuated by the gases produced by the explosion of a cartridge, locking means, located entirely within the body of the weapon, and independent of the breech mechanism, adapted to co-act with a part of the automatic mechanism to prevent the closure of the breech after the last cartridge has been discharged in automatic firing, until the parts are disengaged by a slight backward movement of the sliding part of the breech, said locking means comprising a pawl located in a recess formed in the breech block, a spring for normally retaining such pawl within the recess, a lug, 85 formed on the cartridge lifting cartridge carrier, adapted to engage with and displace said pawl when the last cartridge has been inserted into the barrel, and cause it to project into the path of a projection formed on a part of the automatic mechanism so that the rod is engaged and held by the pawl the moment the breech is fully open.

In testimony whereof I affix my signature in presence of two witnesses.

LUIS MARTINEZ-SILVA.
